UNITED STATES PATENT OFFICE.

WILLIAM H. FLUKER, OF THOMSON, GEORGIA.

ROTARY GRINDING MILL.

Application filed July 15, 1927, Serial No. 206,024. Renewed September 7, 1928.

This invention relates to grinding mills and more particularly to a rotary grinding mill.

It has been proposed to employ grinding mills which include a circular cylinder and partially filled with a predetermined number of balls or rods which, when the shell is rotated, the rods or balls will be agitated in association with the materials for grinding 5 the same. However, in the circular mills there is always a dead center in which the balls are lodged which remains substantially in an idle position so that the materials at these points will not be ground. Furthermore, 10 considerable power is required to operate a mill of this type with less efficient results.

It has also been proposed to provide a mill having a cylindrical shell in which a plurality of chambers are disposed longitudinally with the shell and which are elliptical in cross section. In this type of mill, the chambers are so arranged that they will travel through an arc of a circle around a 20 common center so that only a portion of the rods or balls which are out of contact with the walls of the elliptical chamber will be slowly moved until a predetermined point in the circle of travel of the shell is reached, 25 when the balls or rods will reverse the position and fall from the opposite end of the ellipse. In such a construction dead pockets will be had periodically during each cycle of operation of the mill.

It is an object of the present invention to provide a mill having a shell which is elliptical in cross section and which shell revolves on the axis so that all the rods and balls placed therein will be in continuous movement at all times during the cycle of operation of the elliptical shell.

A further object of the invention is the provision of a grinding mill which is elliptical in cross section and revolving around the 45 common axis of the ellipse so that balls and rods placed therein will not only be maintained in movement at the upper portion thereof, but there will be a continuous movement of all the rods in a definite line at all 50 times, the rods or balls being carried upwardly from the lowest point to the uppermost point continuously, and by gravity fall towards the opposite wall of the elliptical shell.

This invention will be best understood from a consideration of the following detailed de-

scription, in view of the accompanying drawings forming a part of the specification; nevertheless it is to be understood that the invention is not confined to the disclosure, 60 being susceptible of such changes and modifications which shall define no material departure from the salient features of the invention as expressed in the appended claim.

In the drawings:—

Figure 1 is a longitudinal view in elevation of a rotary mill constructed in accordance with the principles of my invention,

Figure 2 is a vertical longitudinal section of the mill,

Figure 3 is a transverse vertical section of the mill when said mill has its major axis in a vertical plane,

Figure 4 is a transverse vertical section of the mill with the major axis in a horizontal 75 plane,

Figure 5 is a transverse vertical section of the mill with the major axis inclined at an angle to the vertical.

Referring more particularly to the drawings 80 10 designates a pair of standards having bearings 11 at their upper ends to support hollow trunnions 12 which are rigidly secured to the opposite end wall 13 or 14 of a shell 15.

The shell, as shown more particularly in Figs. 3 to 5 inclusive, is elliptical in cross section and has an inner liner 16 conforming to the shell 15, and end liners 17 conforming to the end walls 13 and 14 of the mill. The 90 end walls of the shell 15 are provided respectively with cooperating flanges 18 and 19 which are secured together in any approved manner.

The mill is driven by means of a gear 20 95 secured to the trunnions 12 or to the end wall 13, which meshes with a gear 21 secured to a shaft 22 mounted in bearings in one of the standards 10. The shaft 22 is driven by means of a pulley or gear 23 which in turn 100 is rotated from any suitable source of power. The trunnion 12 which is adjacent the gear 20 is provided with a flange 24 to which is bolted, as shown at 25, a feeding device 26. The feeding device has a projection 27 which is adapted to be periodically moved through the ore or materials to be fed to the mill whereby said materials are scooped up by the member 26 and fed through the hollow trunnions to the interior of the mill.

The mill is filled with a plurality of balls or grinding rods 30 to a predetermined depth,

or such a number will be placed therein which will meet the requirements for the grinding of the material. These balls or rods will normally rest upon the lower portion of the mill.

5 The operation of my device is as follows:

The mill is revolved through the gears 21 and 20 on the trunnions 12 so that the elliptical shell will be revolved on a common axis 31. As shown in Fig. 3, the rods have been elevated 10 on the right hand side as the mill continues to revolve in the direction indicated by the arrows. These rods will move downwardly towards the left not only at the outer surface, but there will be a general slide of all of the 15 rods in that direction.

As shown in Fig. 4, the major axis of the elliptical mill is in the horizontal plane and as the mill moves to the vertical position the rods towards the right will slide towards the 20 left and such sliding movement of the rods will be continuous in that direction since not only a portion of the rods are being elevated, but there is a general elevation of the rods on the right hand side, and this continuous 25 slide of the rods or general trend of movement is indicated in Fig. 5, showing the angular movement of the plane of the major axis toward the vertical.

It will be appreciated that the lowermost 30 rods which are in contact with the inner lining of the shell tend to resist to some extent the sliding movement of the rods in the lower portion of the drum so that the elliptical drum in its rotary movement will also tend to build

up somewhat of a pyramid shape of the rods 35 or to maintain the rods in approximately a pyramid during rotation and which is at the right hand side of the mill, as shown in Figs. 3 to 5. The somewhat flattened surface of the mill, due to its elliptical shape tends at all 40 times to provide for this disposition of the rods so that all of the rods are in continuous movement for the most effective grinding of the material. Furthermore not only the top 45 layer of the rods will be shifted but it will be noted from a practical demonstration of such a device that more than a single layer moves in a slide from the extreme upper right to the extreme lower left.

In those cases where it is desired to reconstruct or reform rotary mills of the cylindrical type it will only be necessary to employ the cylindrical shell and insert a liner having a cross sectional area of elliptical formation with the axis of the elliptical liner disposed 55 along the axis of the trunnions 12.

I claim:

A grinding mill having a rotary cylinder uniformly elliptical in cross section throughout the length thereof and provided with 60 trunnions disposed axially of said cylinder the axis of said cylinder being in a horizontal plane, loose gravitationally controlled grinding elements located within the cylinder and normally disposed below a horizontal plane 65 passing through the axis of said cylinder, and means for rotating the shell.

WILLIAM H. FLUKER.
